INVENTOR.

Claes Oscar Meurk,
BY

Robert W. Pearson
ATTORNEY.

Patented July 7, 1925.

UNITED STATES PATENT OFFICE.

CLAES OSCAR MEURK, OF LOS ANGELES, CALIFORNIA.

COOLER BOX.

Application filed November 12, 1923. Serial No. 674,416.

To all whom it may concern:

Be it known that I, CLAES OSCAR MEURK, a citizen of the United States, residing at Los Angeles, in the county of Los Angeles and State of California, have invented certain new and useful Improvements in Cooler Boxes, of which the following is a specification.

My invention relates to cooler boxes, and 10 the objects are first, to provide a self cooling container and storage place in a chamber for food and other perishable materials; second, to provide a storage box with a self contained ventilating system; and third, to construct a cooler box that is simple in construction and inexpensive to maintain.

Other objects and advantages will be made manifest in the following specification with an embodiment of the invention illustrated in the accompanying drawings, in 20 which:

Figure 1 represents a side sectional view on line 2—2 of Figure 2.

Figure 2 represents a plan sectional view 25 on line 1—1 of Figure 1.

Referring to the drawings in which like characters of reference designate similar parts, the cooler 15 comprises an outer-box 1 and an inner-box 2, the inner-box 2 being 30 secured in the outer-box 1 to provide a chamber 3, in the rear, side and top portions of the said cooler 15, as shown in Figures 1 and 2, and the chamber 4 is in the inner-box 2, and the chamber 4 is in communication with 35 the chamber 3 through the passages 9—9^a, chamber 14 and the passages 11—11^a, respectively, and the chamber 3 is in communication with the outside portion of the cooler 15 through the passages 10—10^a, chamber 40 13 and the passages 8—8^a, respectively. The said chamber 13 is positioned in the pocket 6, and the pocket 6 is secured to the upper- 45 inner surface of the outer-box 1 within the said chamber 3, and the pocket 7 is in turn secured to the upper-outer surface of the inner-box 2 within the chamber 3, as shown 50 in Figure 1. The said passages 9—9^a pass through the rear wall of the said inner-box 2 at an angle to one another and point from a parted position in the inner face of the box 2 to a relatively closer position in the adjacent face of the pocket 7, and the passages 55 11—11^a in turn pass downwardly through the pocket 7 from the chamber 14 to the space 3. The passages 10—10^a pass from the

chamber 3, through the pocket 6, to the chamber 13, and the passages 8—8^a pass through the rear wall of the said outer-box 1 at an angle to one another, and point from a parted position in the outer face of the box 1 to a relatively closer position in the adjacent face of the pocket 6. 60

A door 12 is operatively positioned in the front portion of the cooler 15, and the outer-box 1 and inner-box 2 are elevated from the floor line by legs 16 to provide a space 5 thereunder. 65

When air currents pass the rear portion of the cooler 5, as indicated by the arrows, air passes through passage 8 into pocket 6, 70 then from pocket 6 through passage 10^a into chamber 3, through one side of which chamber the air circulates and then passes through passage 11^a into pocket 7, then from pocket 7 through passage 9 into box 2 where 75 the air circulates throughout and then passes out through passage 9^a into pocket 7, then from pocket 7 through passage 11 into chamber 3, through the other side of which chamber the air circulates and then passes 80 through passage 10 into pocket 6 and then from pocket 6 through passage 8^a back into the atmosphere.

When the air current passes the rear portion of the cooler in a direction opposite to that indicated by the arrows, air passes through passage 8^a into pocket 6, then through passage 10 into chamber 3 through one side of which the air circulates and then passes through passage 11 into chamber 7, 90 then through passage 9^a into storage box 2 where the air circulates throughout and then passes through passage 9 into pocket 7, then through passage 11^a into chamber 3, through the other side of which the air circulates and 95 the air passes through passage 10^a into pocket 6 and then through passage 8 back into the atmosphere.

Having thus described my invention what I claim is:

1. A cooler box comprising a storage chamber, an air circulating chamber partly surrounding said storage chamber, a pocket on the outer wall of said air circulating chamber, said pocket being provided with a pair of angularly disposed air passages communicating with the atmosphere and with a pair of air passages communicating with said air circulating chamber, a second pocket on the wall between said storage 105 110

chamber and said air circulating chamber, said second pocket being provided with a pair of passages communicating with said air circulating chamber, and with a pair of angularly disposed passages communicating with said storage chamber.

2. A cooler box comprising a storage chamber, an air circulating chamber partly surrounding said storage chamber, a pocket 10 on the outer wall of said air circulating chamber, said pocket being provided with a pair of passages communicating with the atmosphere and with a pair of passages communicating with said air circulating chamber, a second pocket on the wall between said storage chamber and said air circulating chamber, said second pocket being provided with a pair of passages communicating with said air circulating chamber, and

with a pair of passages communicating with 20 said storage chamber.

3. A cooler box comprising a storage chamber, an air circulating chamber partly surrounding said storage chamber, a pocket 25 on the outer wall of said air circulating chamber, said pocket being provided with a pair of passages communicating with the atmosphere and with a pair of passages communicating with said air circulating chamber, a second pocket below said first 30 pocket on the wall dividing said chambers, said second pocket having a pair of passages communicating with said air circulating chamber and with a pair of passages communicating with said storage chamber. 35

In testimony whereof I affix my signature.

CLAES OSCAR MEURK.
